UNITED STATES PATENT OFFICE.

ARTHUR M. WAITT, OF CLEVELAND, OHIO.

CLEANING AND POLISHING COMPOSITION.

SPECIFICATION forming part of Letters Patent No. 663,479, dated December 11, 1900.

Application filed March 28, 1899. Serial No. 710,268. (No specimens.)

To all whom it may concern:

Be it known that I, ARTHUR M. WAITT, a resident of Cleveland, county of Cuyahoga, and State of Ohio, have invented certain new and 5 useful Improvements in Liquid Compounds for Cleaning and Polishing Varnished Surfaces; and I do hereby declare the following to be a full, clear, and exact description of the invention, such as will enable others skilled 10 in the art to which it pertains to make and use the same.

My invention relates to an emulsion-forming compound more especially adapted for cleaning and polishing varnished surfaces. 15 The object of this invention is to provide a compound of the character indicated that is a powerful dirt-remover, that is not liable to injure the varnish nor harmful in any other manner, and that does not require care 20 and skill in its application.

The compound consists, essentially, of refined petroleum whose specific gravity is 32° Baumé or about 32° Baumé and diluted muriatic or hydrochloric acid mixed in the proportions of about one part of the petroleum to two parts of the diluted acid. The diluted acid consists, preferably, of about one part of acid whose specific gravity is about 20° Baumé and two parts of water and is consequently not injurious to varnish. 25

The compound having the aforesaid ingredients in the aforesaid proportion is capable of cleaning and polishing any varnished surface, and a varnished surface having the 30 most obstinate coat of dirt is readily cleaned upon the application of the compound thereto.

The compound when the same is designed for use in cleaning and polishing the varnished surfaces of furniture may contain 35 less acid or more water than indicated by the proportion hereinbefore specified.

The two ingredients, the petroleum and the diluted acid, are mixed by suitable agitation, and the agitation that is preferably employed

is effected by the introduction of compressed 45 air in the manufacture of a large quantity of the compound, because the use of compressed air facilitates the mixture of the ingredients and renders the mixture of the acid with the petroleum gradual. The petroleum is very 50 effective in preventing the corrosive action of the acid, and refined petroleum of 32° Baumé mixed with the diluted acid forms a permanent emulsion—that is, the emulsive character of the compound does not disappear by allowing the compound to stand an 55 indefinite time.

The distinctive and essential characteristic of the compound that constitutes the subject-matter of this application is the formation 60 of a permanent emulsion composed of refined petroleum and the diluted acid, and this characteristic can only be attained by using refined petroleum of 32°, or approximately 32°, Baumé and by mixing the petroleum and the diluted acid in about one part of the petroleum to two parts of the diluted acid. In fact, the use of refined petroleum 65 of 32° Baumé gives the best results.

What I claim is—

1. A permanent emulsion consisting of refined petroleum having a specific gravity of 32° or about 32° Baumé, and diluted acid that is not injurious to varnish, and having the said ingredients mixed in the proportions 75 of about one part of the petroleum to two parts of the diluted acid.

2. A permanent emulsion containing refined petroleum having a specific gravity of 32° or about 32° Baumé, and diluted hydrochloric acid, in the proportion of about one part of the petroleum to two parts of the acid. 80

Signed by me at Cleveland, Ohio, this 15th day of March, 1899.

ARTHUR M. WAITT.
